DESIGN FOR A RIBBON INSERTION

Ernest A. Mills, New York, N. Y.

Application December 5, 1940, Serial No. 97,082

Term of patent 3½ years

To all whom it may concern:

Be it known that I, Ernest A. Mills, a citizen of the United States and residing in Manhattan, in the city, county, and State of New York, have invented a new, original, and ornamental Design for a Ribbon Insertion, of which the following is a specification, reference being had to the accompanying drawing, forming part thereof, wherein

The figure is a plan view of the insertion showing my new design.

I claim:

The ornamental design for a ribbon insertion, substantially as shown.

ERNEST A. MILLS.
